UNITED STATES PATENT OFFICE.

THOMAS HENRY McCauley, of CALGARY, ALBERTA, CANADA.

CAR-BRAKE-OPERATING MECHANISM.

1,285,282.

Specification of Letters Patent. Patented Nov. 19, 1918.

Application filed February 15, 1917, Serial No. 148,894. Renewed April 30, 1918. Serial No. 231,748.

To all whom it may concern:

Be it known that I, THOMAS HENRY McCauley, a subject of the King of England, residing at Calgary, in the Province of Alberta and Dominion of Canada, have invented a new and useful Car-Brake-Operating Mechanism, of which the following is a specification.

The present invention appertains to car brakes, and relates more particularly to the operating devices thereof.

It is the object of the invention to provide a novel and improved attachment for such devices, and operable for storing up energy or power to operate said device and apply the brakes quickly and easily, the present mechanism also being of advantage for quickly applying the brakes in case of emergency, and for conveniently restoring or releasing the brakes.

With the foregoing and other objects in view, which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawings, wherein:

Figure 1 is a perspective view of the invention as applied to a common form of brake operating device.

Fig. 2 is a front view illustrating a variation as applied to a different form of brake operating device.

Fig. 3 is a side elevation of the mechanism shown in Fig. 2, portions being broken away and shown in section.

Fig. 4 is a perspective view of another modification as applied to a still different form of brake operating device.

Referring to Fig. 1, there is illustrated therein the upright brake operating staff or shaft 1 journaled through the floor or deck 2 of the car, and through a suitable bracket 3 above the floor or deck, the usual hand wheel 4 being secured upon the upper end of the shaft 1. A chain or other flexible element 5 is connected to the lower terminal of the shaft 1 to be wound thereon for applying the brakes in the ordinary manner, the wheel 4 being rotated in the direction of the

arrow for applying the brakes. A ratchet wheel 6 is secured upon the shaft 1 above the deck 2 and is adapted to be engaged by a pawl or dog 7 for holding the shaft 1 and preventing the chain 5 from unwinding when the brakes are applied and by rotating the hand wheel 4 slightly in the direction of the arrow, the pawl 7 will be disengaged from the ratchet wheel 6, thereby enabling the shaft 1 to rotate for unwinding the chain and releasing the brake. The foregoing device is common and well known.

In carrying out the invention, a coiled torsional spring 8 surrounds the shaft 1 and has its lower end secured, as at 9, to the shaft while the upper end of the spring is secured, as at 10, to the bracket 3 or other stationary member, this spring 8 being arranged to be wound up when the chain 5 is unwound, thereby storing energy in the spring for subsequently applying the brakes quickly and effectively.

As a means for rotating the shaft 1, to release the brakes and wind up the spring 8, a drum 12 is secured upon the shaft 1 in any suitable manner, preferably above the bracket 3, and has attached thereto a cord, cable or other flexible element 13 which is adapted to be wound thereon as the shaft 1 is rotated for winding up the chain 5. The cord 13 passes over a pulley wheel 14 carried by the bracket 3 and has its free end attached to a vertically movable slide 15, said slide having a sleeve 16 guided for vertical movement upon a guide rod 17. Said guide rod is attached to the deck 2 and bracket 3, as illustrated, and the slide 15 has a foot piece 18 projecting laterally from the sleeve 16. It is evident that when the cord 13 is wound upon the drum 12, the slide 15 is raised, and by depressing the slide by the foot, the cord will be pulled downwardly, thereby unwinding it from the drum 12 and rotating the shaft 1 to wind up the spring 8 and unwind the chain 5 so as to release and reset or restore the brakes.

A second dog or pawl 19 is mounted upon the deck 2 adjacent to the ratchet wheel 6 for locking the shaft 1 against rotation when the spring 8 is wound up, the pawl 19 preventing the shaft 1 from rotating to apply the brakes under the influence of the spring, while the pawl 7 is for the purpose of holding the shaft against rotation when the brakes are applied. These pawls can be

readily operated by the foot of the operator for bringing them into engagement with the ratchet wheel 6, when desired or necessary.

In operation, when the slide 15 is depressed, the shaft 1 is rotated, as above described, for winding up the spring 8 and unwinding the chain 5 to release and restore the brakes, the pawl 19 then being moved into engagement with the ratchet wheel 6 for holding the spring 8 wound up. To apply the brakes, the hand wheel 4 is rotated slightly in a direction opposite to that indicated by the arrow, thereby releasing the pawl 19 from the ratchet wheel 6 and the spring 8 will then assert itself and rotate the shaft 1 for winding up the chain 5, thereby applying the brakes and, if desired, the operator can give the wheel 4 a further turn to tighten the grip of the brakes, the pawl 7 being moved into engagement with the ratchet wheel 6 for holding the brakes applied. During this rotation of the shaft, the cord 13 is wound upon the drum 12, and to again release the brakes and wind up the spring 8, the hand wheel 4 is rotated slightly in the direction of the arrow to release the pawl 7 and after which the slide 15 is depressed as above described.

The present improvements can be readily incorporated in the common brake operated device illustrated in Fig. 1, and relieves the operator, to a large extent, in applying the brakes, no manual effort on the part of the operator being necessary unless it is desired to further rotate the shaft 1 after the spring has unwound. The manual effort is directed to winding up the spring and releasing the brake, which does not require the quick action necessary for applying the brakes, especially in the case of emergency.

Figs. 2 and 3 illustrate the improvements applied in a slightly different manner to a different form of brake operating device, which has a short horizontal brake operating shaft 1' carried by the upper end of a standard or stand 3', the brake wheel 4' being secured upon the front terminal of the shaft 1' in a vertical plane, and the ratchet wheel 6' being carried by the shaft 1' immediately in rear of the wheel 4'. The opposite pawls or dogs 7' and 19' are pivoted to the standard 3' to engage the ratchet wheel 6', and the torsion spring 8' surrounds the rear terminal of the shaft 1' and has one end connected thereto, as at 9', and its other end secured, as at 10', to a casing 11 carried by the standard 3' and inclosing the spring and shaft, as seen in Fig. 3. The drum 12' is secured to the forward end of the shaft 1' immediately in front of the hand wheel 4', and the cord or flexible element 13' which is secured to and wound upon the drum is connected to the vertically movable slide 15' having the sleeve 16' slidable upon the standing or vertical guide rod 17', the slide

having the foot piece 18' adapted to be depressed by the foot. In order that the pawls 7' and 19' can be operated by the foot, they are connected by links 20, which are preferably crossed, with foot levers 21 of angular form having their elbows fulcrumed upon the case of the standard 3' or the floor. These foot levers can be operated for moving the pawls into engagement with the ratchet wheel, the same as the pawls 7 and 19 above described. The operation is practically the same as that above described, the hand wheel 4' being rotated in the direction of the arrow in Fig. 2 for applying the brakes, and being rotated in this direction by the spring 8', which is wound up by the depression of the slide 15'.

The invention is illustrated as being applied to still another form of brake operating device, as seen in Fig. 4, this device embodying a casting or frame 3^a from which the brake staff or shaft 1^a extends upwardly. Carried by the frame 3^a is a gear wheel 6^a which also serves as a ratchet wheel, the shaft 1^a extending downwardly through the wheel 6^a for rotating it. The wheel 6^a meshes with a gear wheel 6^b having the drum 6^c for winding up the chain 5^a to apply the brakes. A torsional spring 8^a surrounds the lower depending terminal of the shaft 1^a and has one end secured, as at 9^a, to the shaft, while its other end is secured to a bar 11^a attached to the lower ends of depending bolts or rods 11^b carried by the frame 3^a at opposite sides of the shaft 1^a. The drum 12^a is secured upon the shaft 1^a above the frame 3^a and has a rope or flexible element 13^a connected thereto for winding up the spring, and the pawls are preferably mounted upon the rods 11^b, one pawl 19^a being illustrated, and serving to engage the wheel 6^a for preventing the spring from unwinding. The pawls can be moved into engagement with the ratchet wheel in any suitable manner. The other pawl which is engageable with the gear wheel 6^a for holding the device when the brakes are applied, is opposite to the pawl 19^a and is of similar construction but in reversed position, as will be apparent from the foregoing. The operation of this mechanism is substantially the same as the operation of the other two mechanisms, and need not be described at length.

Having thus described the invention, what is claimed as new is:

1. The combination with a brake operating device including a shaft for operating the brakes, and a hand wheel connected to the shaft, of spring means connected to the shaft to be wound up thereby when the shaft is rotated to release the brakes, means for holding the shaft when the spring is wound up, and means independent of said wheel connected to the shaft for rotating it to release the brakes and wind up the spring.

2. The combination with a brake operating device including a shaft for operating the brakes, of spring means connected to said shaft to be wound up when the shaft is rotated for releasing the brakes, means for holding said shaft when the spring is wound up, a drum connected to said shaft, a compressible slide, and a flexible element connected to said slide and attached to and wound upon said drum for rotating the shaft to release the brakes and wind up the spring when said slide is depressed.
- 5 In testimony that I claim the foregoing as my own I have hereto affixed by signature in the presence of two witnesses.

THOMAS HENRY McCauley.
